(57) **CLAIM**

The ornamental design for tracheostoma device as shown and described.

DESCRIPTION

1.1 : Back view illustrating a tracheostoma device;
1.2 : Perspective view illustrating the tracheostoma device;
1.3 : Right view illustrating the tracheostoma device;
1.4 : Bottom view illustrating the tracheostoma device;
1.5 : Front view illustrating the tracheostoma device;
1.6 : Left view illustrating the tracheostoma device; and
1.7 : Top view illustrating the tracheostoma device.
